UNITED STATES PATENT OFFICE.

JOHN VAN DEN BOS, OF GRAND RAPIDS, MICHIGAN.

CARBURETER.

1,226,929.

Specification of Letters Patent. Patented May 22, 1917.

Application filed December 30, 1915. Serial No. 69,436.

To all whom it may concern:

Be it known that I, JOHN VAN DEN Bos, a citizen of the United States, residing at Grand Rapids, in the county of Kent and State of Michigan, have invented certain new and useful Improvements in Carbureters; and I do declare the following to be a full, clear, and exact description of the invention such as will enable others skilled in the art to which it appertains to make and use the same.

My invention relates to improvements in carbureters and more particularly to those designed for utilizing either gasolene or kerosene, the object of the invention being to improve and simplify the general construction of carbureters of this class in a number of ways.

With this general object in view, the invention resides in certain novel features of construction, and in unique combinations of parts to be hereinafter fully described and claimed, the descriptive matter being supplemented by the accompanying drawings which constitute a part of this application and in which,

Figure 1 is a side elevation of a carbureter constructed in accordance with the invention;

Fig. 2 is a central vertical longitudinal section thereof;

Fig. 3 is a horizontal sectional view taken approximately on the plane indicated by the line 3—3 of Fig. 1;

Fig. 4 is a central vertical transverse section as viewed on the line 4—4 of Fig. 1;

Fig. 5 is a fragmentary top plan with parts in section; and

Fig. 6 is a horizontal sectional view taken on the planes of the irregular line 6—6 of Fig. 4.

In specifically describing the construction shown in the drawings above briefly described, similar reference characters will be placed on corresponding parts throughout the several views and reference will be herein made to the numerous elements by their respective indices. To this end, the numeral 1 indicates an upright one-piece tube having a laterally extending flange 2 at its upper end adapted to be secured to the intake manifold of an internal combustion engine, the lower end of said tube being disposed in a horizontal plane and provided with a cup-shaped

closure 3 whose upper edge is formed with an upstanding annular flange 4 spaced inwardly from said edge and received snugly within the lower extremity of the tube 1. Diametrically opposite points on the exterior of the closure 3 are provided with laterally extending ears 4' which underlie appropriate bosses 5 formed integrally with the lower end of the tube, screws 6 being passed through said ears and into the bosses as shown clearly in Fig. 2.

Formed integrally with and projecting horizontally from the curved wall of the closure 3, is a hollow air intake neck 7, said neck having its outer end curved upwardly as disclosed at 8 in Fig. 4 and flared outwardly to form a bell mouth 9 terminating in a horizontal plane, the upper edge of said mouth being provided with a plurality of radiating horizontal arms 10 formed integrally therewith at their outer ends and similarly joined to a central enlargement 11 at their inner ends. An appropriate valve plate 12 overlies the arms 10 and is secured in position by a set screw 13 passed loosely through its center and threaded into the enlargement 11. Thus, when the screw is loosened, the plate 12 may be turned to properly regulate the amount of air entering the tube 1 through the neck 7, and when this adjustment has been made, tightening of the screw in question will prevent further movement of the valve plate.

The interior diameter of the tube 1 is contracted intermediate its ends as disclosed at 14 for the anchorage of a Venturi tube 15 through which air drawn from the neck 7 through the tube 1 must pass, any preferred type of fuel spray nozzle 16 being disposed centrally in the contracted portion of said Venturi tube. The nozzle 16 is carried by the upper end of an upright tubular nipple 17 which rises from and is formed integrally with the center of a horizontal fuel tube 18, the latter being formed integrally with the tube 1 and extending diametrically across the interior thereof in a plane below the Venturi tube 15.

Formed integrally with the center of the tube 18 and depending therefrom is an upright valve tube 19 whose lower end is passed through a central opening 20 formed in the bottom of the closure 3. Threaded in the lower end of the tube 19 is a packing gland

21 through which an upright needle valve 22 is threaded, said valve being received in the tube 19 and having a pointed upper end designed for coöperation with the bore of the nipple 17 in order that the passage of fuel from the tube 18 into said nipple may be accurately regulated.

22 The lower end of the valve 22 is provided with a peripherally notched disk 23 whereby it may be rotated at will, the notches of said disk coöperating with an upright spring detent 24 whereby the valve will be yieldably held in adjusted position. The upper end of the detent 24 is provided with a horizontal attaching plate 25 which contacts with the bottom of the closure 3, being formed with a central opening through which the externally threaded lower end of the tube 19 projects. A nut 26 is threaded on said end 23 of the tube 19 and clamps the plate 25 between itself and the bottom 3.

24 From the immediately preceding description, it will be observed that the tube 19 serves not only as a casing for the needle valve 22 but as an effective anchor for the detent 24, this two-fold function of the tube in question being considered a rather important feature of the invention. Furthermore, since the nut 26 is threaded tightly on the tube 19 beneath the closure 3, it may well be used in some cases as the sole means of securing said closure to the lower end of the tube 1. However, in order to prevent the closure in question from having any tendency whatever to turn, the screws 6 will preferably be employed.

25 Projecting laterally from and formed integrally with the upper end portion of the tube 1, is a hollow supplemental air inlet neck 27, said neck being equipped with any preferred type of suction opened spring closed valve 28. It is desirable, however, that the neck 27 be disposed directly above the neck 7, thus leaving the opposite side of the tube 1 free of projections.

26 Spaced in opposite directions from the tube 1, preferably in directions extending at right angles to the necks 7 and 27, is a gasolene reservoir 29 and a kerosene reservoir 29^a, the two being provided respectively with fuel inlets 30 and 30^a controlled automatically by float actuated valves 31 and 31^a, the construction and operation of these valves being too well known to herein require explanation. The upper ends of the reservoirs 29 and 29^a are spaced from the tube by integral necks 32 and 32^a, while the lower ends of said reservoirs are in turn connected with the tube 1 by integral tubular necks 33 and 33^a whose bores coincide with the bore of the tube 18 and lead to said tube from the two reservoirs.

27 Plug valves 34 and 34^a are provided in the bores of the necks 33 and 33^a, said valves 28 being equipped on one end with parallel

29 operating arms 35 and 35^a connected by a link 36, whereby the two valves may be moved in unison by shifting of said link. The valves in question are so related as to cause one to be closed when the other is 70 opened, thus allowing either gasoline or kerosene to be used when desired.

30 The operating arms 35 and 35^a are preferably formed with enlargements through which transverse stop screws 37 and 37^a are 75 passed, said screws being adapted for contact with appropriate stops 38 and 38^a cast integrally with and extending laterally from the lower ends of the fuel reservoirs. By this means, all danger of improper positioning of the valves 34 and 34^a is prevented.

31 From the foregoing description and a careful inspection of the accompanying illustrations, it will be observed that the improved carburetor has been embodied in a 80 much more simple form than those heretofore used for the consumption of two or more grades of fuel. Regardless of this extreme simplicity, however, no advantages have been sacrificed. In fact, the device 85 will be more rather than less efficient, due to the absence of complicated parts.

32 In conclusion, I will state that although the drawings illustrate the preferred embodiment of my invention, numerous 90 changes may be made within the scope of the appended claims without sacrificing the primary objects of the device.

33 I claim:—

34 1. A carburetor comprising a vertically 100 disposed passage member to be connected at its upper end with an intake manifold, a pair of necks extending horizontally in diametrically opposite directions from the lower end of said passage member and having reservoirs at their outer ends for supplying different fuels to the passage member, an air inlet neck extending horizontally from the lower end of the passage member at right angles to the other necks, an auxiliary air inlet neck extending horizontally from the upper end of said passage member in the same direction as the aforesaid air inlet neck, these two necks being of substantially the same length, a pair of rocking valves 105 extending through the fuel supply necks, parallel operating arms rising from said valves, and a horizontal operating link connecting said arms for simultaneous movement and disposed between the two air inlet necks.

35 2. In a two-fuel carburetor, a vertical passage member to be connected at its upper end with an intake manifold, said passage member having at its lower end a pair of 115 horizontal fuel supply necks extending in opposite directions and fuel reservoirs on the outer ends of said necks; in combination with valves for said necks having vertically 120 extending operating arms connected for si- 130

multaneous movement, stops formed integrally with the lower ends of said reservoirs in the outward paths of said arms, and other stops carried by said arms and arranged to strike those of the reservoirs to limit the movement of the valves.

5 In testimony whereof I have hereunto set

my hand in presence of two subscribing witnesses.

JOHN VAN DEN BOS.
